UNITED STATES PATENT OFFICE.

WILLIAM L. LIBBEY, OF BOSTON, MASSACHUSETTS, ASSIGNOR TO NEW ENGLAND GLASS COMPANY, OF SAME PLACE.

DESIGN FOR A LAMP-SHADE.

Specification forming part of Design No. 7,023, dated December 9, 1873; application filed November 10, 1873.
[Term of Patent 3½ years.]

To all whom it may concern:

Be it known that I, WILLIAM L. LIBBEY, of Boston, in the county of Suffolk and State of Massachusetts, have invented a Design for Glass-Lamp Shades, of which the following is a specification:

The nature of my design is fully represented in the accompanying drawing.

In the said drawing, A denotes the main portion or body of the shade, which is of a hollow hexagonal form, made with vertical sides, terminating at their upper ends in a curved hexagonal neck or opening, B, of less diameter than that of the body. At its lower end the body is bounded by a curved contracted portion, C, of a hexagonal shape, having its corners or angles in the same vertical planes with those of the main portions A. The extremity of the part C terminates in a curved meniscus-shaped flange, α ; but the flange may be dispensed with, without departing from the spirit of my invention, which

consists in the peculiar shape of the body portion A, the neck B, and the lower portion C—that is, making the body of a hexagonal shape, surmounted by a curved hexagonal neck, and the lower portion with curved contracted sides, having their corners or angles in the same vertical planes with those of the body portion.

Having described my invention, what I claim is—

The design for glass-lamp shades, consisting in the body A with hexagonal sides, surmounted by a curved hexagonal neck, B, and having the portion C formed with curved contracted sides, having their corners or angles in the same vertical planes with those of the body portion, as shown and described.

WILLIAM L. LIBBEY.
